UNITED STATES PATENT OFFICE.

GEORGE C. LUCAS, OF CLEVELAND, OHIO.

SWITCH-ROD MECHANISM.

No. 830,089.

Specification of Letters Patent.

Patented Sept. 4, 1906.

Application filed May 28, 1906. Serial No. 319,123.

To all whom it may concern.

Be it known that I, GEORGE C. LUCAS, a citizen of the United States of America, residing at Cleveland, in the county of Cuyahoga and State of Ohio, have invented certain new and useful Improvements in Switch-Rod Mechanism; and I hereby declare the following to be a full, clear, and exact description of the invention, such as will enable others skilled in the art to which it pertains to make and use the same.

This invention relates to improvements in switch-rod mechanism, and pertains more especially to a safety switch-rod mechanism comprising a bracket which is adapted to be secured to one of the switch-rails, a switch-rod adapted to be secured to the other switch-rail, and an upright adjusting-bolt extending loosely through the switch-rod, with the bracket extending over and under the bolt-engaged portion of the switch-rod, with two eccentrics formed upon or operatively connected with the bolt and arranged within and operatively connected with the bracket at the top and bottom, respectively, of the switch-rod, so that the said members are adjusted relative to each other by simply turning the bolt without necessitating any withdrawal or endwise shifting of the bolt.

Another object is to provide the switch-rod with a wrench-forming plate or bar which is removably attached to the switch-rod and is provided with a portion overhanging the aforesaid bracket, with the bracket-overhanging portion of the bar operatively connected with but removable from the aforesaid adjusting-bolt, so that the said bar is not only instrumental in locking the adjusting-bolt against being turned accidentally, but upon detachment from the switch-rod can be manipulated as a wrench in turning the bolt to change the relative adjustment of the bracket and switch-rod.

Another object is to provide the adjusting-bolt with two coöperating eccentrics arranged, respectively, above and below the switch-rod, and thereby form a desirable and adequate operative connection between the bracket and the bolt both above and below the switch-rod.

Another object of this invention is to render the means employed in relatively ad-

justing the bracket and the switch-rod simple and durable in construction and convenient, safe, and reliable in its operation.

55

With these objects in view and to the end of realizing other advantages hereinafter appearing this invention consists in certain features of construction and combinations of parts hereinafter described, and pointed out in the claims.

In the accompanying drawings, Figure 1 is a top plan of switch-rod mechanism embodying my invention. Fig. 2 is a side elevation, largely in central longitudinal section. In Fig. 2 the bracket of the switch-rod mechanism is shown attached to one of the switch-rails, which is shown in position relative to one of the main rails of a railway-track. Figs. 3 and 4 are horizontal sections on lines 70 3 3 and 4 4, respectively, Fig. 2, looking downwardly.

Referring to the drawings, A indicates a bracket which is adapted to be secured to one of the switch-rails. The bracket A is only shown secured to the connected switch-rail B in Fig. 2, which also illustrates the said switch-rail in position relative to the adjacent main rail C of a railway-track. The bracket A is provided with a recessed portion a, which is provided centrally between the upper and lower surfaces thereof with a recess 5, which is arranged horizontally and extends longitudinally of and laterally through the said recessed portion of the bracket. The recess 5 is engaged by the switch-rod D, which is adapted to be secured to the other switch-rail in the usual manner. The switch-rod D extends laterally through the recess 5.

An upright adjusting-bolt G, employed in adjusting the bracket A and switch-rod D relative to each other, extends vertically through the recessed portion a of the said bracket and through a circular hole d formed in the switch-rod. The bolt G is provided with a square or polygonal head g, which overlaps and rests upon and is arranged wholly externally of the recessed portion a of the bracket A. Next below its head g the bolt has an integral eccentric portion 8, which snugly engages a circular hole 6 in the top wall of the recess 5 and is arranged wholly externally and above the switch-rod.

90

95

100

D. The shank of the bolt snugly engages but is turnable within the hole *b* in the switch-rod and below the switch-rod is provided with a flat side 12 and a downwardly-facing shoulder 13 at the upper end of the flat surface 12. The flattened portion of the bolt is provided with an eccentric 14, which is operatively connected with the bolt, being provided internally with a flat surface 15, which 5 overlaps and conforms to the flat side 12 of the bolt-shank. The eccentric 14 coöperates with the eccentric 8 and snugly occupies a circular hole 7 in the bottom wall of the recess 5 and is arranged wholly externally of 10 and below the switch-rod D. It will be observed, therefore, that the adjusting-bolt is provided with two eccentrics which have a corresponding throw and are arranged within the bracket at the top and bottom, respectively, of the switch-rod and in line vertically and that the switch-rod and the bracket are 15 adjusted relative to each other by turning the adjusting-bolt. The lower end of the shank of the bolt is screw-threaded, and a 20 correspondingly-threaded nut *h* is mounted on the said shank next below the recessed portion *a* of the bracket. The nut *h* and the head *g* of the bolt coöperate with the bracket in forming stops for preventing endwise 25 shifting of the adjusting-bolt. The lower eccentric 14 is provided at its upper end with an external annular shoulder 16, which is seated within a correspondingly annular enlargement of the upper end of the hole 7, and 30 hence the eccentric is supported at its shoulder 16 from the bracket.

To lock the adjusting-bolt in the desired adjustment, a wrench-forming plate or bar K is provided, which bar rests upon the switch-rod in suitable proximity to the recessed portion 35 *a* of the bracket A and is detachably secured to the switch-rod by a suitably-applied bolt *l* and nut *m*. The bar K is arranged longitudinally of the switch-rod and has one 40 end portion thereof raised and overhanging or overlapping the recessed portion *a* of the bracket and provided with a hole *k*, which extends vertically through the bracket-overhanging portion of the bar and is snugly engaged by and conforms to the head *g* of the bolt. As the adjusting-bolt in the construction illustrated has a square head, the hole *k* in the bracket-overhanging portion of the bar is also square. The bar K is therefore not 45 only removably secured to but detachable from the switch-rod and is operatively connected with and removable from the adjusting-bolt, and consequently the said bar upon detaching it from the switch-rod by removing 50 the bolt *l* and nut *m* can be manipulated as a wrench in turning the adjusting-bolt to effect any required relative adjustment of the switch-rod and bracket. Obviously an 55 adjusting-bolt having a square head, as

shown, is given a quarter-turn at a time in 60 readjusting the bolt, and the wrench-forming member K upon lifting it from the bolt after a readjustment of the bolt can be reapplied to the head of the bolt in the position required to accommodate a reattachment of 65 the said wrench-forming member to the switch-rod by the bolt *l* and nut *m*.

By the construction hereinbefore described it will be observed that the bracket is not only adjustable endwise of the switch-rod, 70 but the adjusting-bolt is operatively connected with the bracket both above and below the switch-rod; that the said bolt does not have to be removed or shifted endwise to relatively readjust the bracket and switch-rod; 75 that the construction is safe, and that the means employed in locking the adjusting-bolt to the switch-rod is simply and efficiently composed of a wrench-forming member 80 removably secured to but conveniently detachable from the switch-rod and having a portion embracing and conforming to but removable from the polygonal head of the bolt.

What I claim is—

1. In switch-rod mechanism, the combination, with a switch-rod adapted to be secured to one of the switch-rails, and a bracket overlapping the upper and under sides and adjustable endwise of the rod and adapted to be secured to the other switch-rail, of an adjusting-bolt extending through the rod-overlapping portions of the bracket and loosely through the rod, which bolt has an integral eccentric portion snugly arranged and turnable within the bracket above the rod; a suitably-supported eccentric operatively mounted on the bolt and arranged snugly and turnable within the bracket below the rod, which eccentric has the dimensions and arrangement required to render it capable of coöperating with the first-mentioned eccentric, and means for locking the bolt against rotation.

2. In switch-rod mechanism, the combination with a switch-rod adapted to be secured to one of the switch-rails and having a bolt-hole, and a bracket overlapping the rod at the ends of the said bolt-hole and adjustable endwise of the rod and adapted to be secured to the other switch-rail, of an adjusting-bolt extending through the rod-overlapping portions of the bracket and loosely through the aforesaid bolt-hole, which bolt has an integral eccentric portion snugly arranged and turnable within the bracket at one end of the aforesaid bolt-hole and has a flat side within 100 the bracket at the other end of the said bolt-hole; a suitably-supported eccentric mounted on the bolt and arranged snugly and turnable within the bracket at the last-mentioned end of the said bolt-hole, which eccentric is 105 provided with an internal flat surface opposite the flat side of the bolt and has the dimensions and arrangement required to ren 110

115

120

125

der it capable of coöperating with the first-mentioned eccentric, and means for locking the bolt against rotation.

3. In switch-rod mechanism, the combination, with a switch-rod adapted to be secured to one of the switch-rails and having a bolt-hole, and a bracket overlapping the rod at the ends of the said bolt-hole and adjustable endwise of the rod and adapted to be secured to the other switch-rail, of an adjusting-bolt extending through the rod-overlapping portions of the bracket and loosely through the aforesaid bolt-hole, which bolt has an integral eccentric portion snugly arranged and turnable within the bracket at one end of the aforesaid bolt-hole; a suitably-supported eccentric operatively mounted on the bolt and arranged snugly and turnable within the bracket at the outer end of the said bolt-hole, 20 which eccentric has the dimensions and arrangement required to render it capable of coöperating with the first-mentioned eccentric; means for preventing endwise displacement of the bolt, and means for locking the bolt against rotation.

4. In switch-rod mechanism, the combination, with a switch-rod adapted to be secured to one of the switch-rails and having a bolt-hole, and a bracket overlapping the rod at the ends of the said bolt-hole and adjustable endwise of the rod and adapted to be secured to the other switch-rail, of an adjusting-bolt extending through the rod-overlapping portions of the bracket and loosely through the aforesaid bolt-hole, which bolt is operatively provided with two coöperating eccentrics snugly arranged and turnable within the bracket at opposite ends respectively of the said bolt-hole; means for preventing endwise displacement of the bolt, and means for locking the bolt against rotation.

5. In switch-rod mechanism, the combination, with a bracket adapted to be secured to one of the switch-rails, which bracket is provided with a switch-rod-receiving recess extending laterally through the recessed portion of the bracket, and a switch-rod extending laterally through the recess and adapted to be secured to the other switch-rail, of an adjusting-bolt extending through the top wall and bottom wall of the recess and loosely through the switch-rod and provided with a head overlapping the upper side of the said top wall, which bolt has an integral eccentric portion snugly arranged and turnable within the last-mentioned wall; a suitably-supported eccentric operatively mounted on the bolt and snugly arranged and turnable in the aforesaid bottom wall and adapted to coöperate with the first-mentioned eccentric, and a nut on the bolt under the lower surface of the recessed portion of the bracket.

6. In switch-rod mechanism, the combination, with a bracket adapted to be secured to one of the switch-rails, which bracket is pro-

vided with a switch-rod-receiving recess extending laterally through the recessed portion of the bracket, and a switch-rod extending laterally through the said recess and adapted to be secured to the other switch-rail, of an adjusting-bolt extending through the top wall and bottom wall of the recess and loosely through the switch-rod and having an integral eccentric portion snugly arranged and turnable within the aforesaid top wall; an eccentric operatively mounted on the bolt and snugly arranged and turnable within the aforesaid bottom wall, which eccentric is adapted to coöperate with the first-mentioned eccentric and has an external annular shoulder seated in the bracket, and means for locking the bolt against rotation.

7. In switch-rod mechanism, the combination, with a switch-rod adapted to be secured to one of the switch-rails and having a bolt-hole, and a bracket overlapping the rod at the ends of the said bolt-hole and adjustable endwise of the rod and adapted to be secured to the other switch-rail, of an adjusting-bolt extending through the rod-overlapping portions of the bracket and loosely through the aforesaid bolt-hole, which bolt is operatively provided with two eccentrics snugly arranged and turnable within the bracket at opposite ends respectively of the said bolt-hole; means for turning the bolt, and means for locking the bolt-turning means to the switch-rod.

8. In switch-rod mechanism, the combination, with a bracket adapted to be secured to one of the switch-rails, and a switch-rod adapted to be secured to the other switch-rail, of an adjusting-bolt extending loosely through the bracket and loosely through the switch-rod and having a polygonal head arranged wholly exteriorly of the bracket, which bolt is provided with an eccentric within the bracket, and a wrench-forming plate or bar removably secured to the switch-rod adjacent to the bracket and having a portion which overlaps the bracket and has a hole engaged by and conforming to the head of the bolt.

9. In switch-rod mechanism, the combination, with a bracket adapted to be secured to one of the switch-rails, and a switch-rod adapted to be secured to the other switch-rail, of an adjusting-bolt extending loosely through the bracket and loosely through the switch-rod and having a head arranged wholly externally of the bracket, which bolt is provided with an eccentric portion within the bracket, and a wrench-forming member removably secured to the switch-rod adjacent the bracket and having a portion which overlaps the bracket and is operatively connected with the head of the bolt but removable from the said head upon detaching the wrench-forming member from the switch-rod.

10. In switch-rod mechanism, the combi-

130

nation, with a bracket adapted to be secured to one of the switch-rails, and a switch-rod adapted to be secured to the other switch-rail, and an eccentric-bolt for relatively adjusting the switch-rod and bracket, of a wrench-forming plate or bar operatively connected with the bolt and removably secured to the switch-rod.

In testimony whereof I sign the foregoing specification in the presence of two witnesses.

GEORGE C. LUCAS.
